* Henry G. Guyon : New York City

Letters Patent

The Schedule referred to in these Letters Patent and making part of the same containing a description in the words of the said Henry G. Guyon himself of his improvement in the compound Lever for Lifting and raising substance.

It is known that Henry G. Guyon of the City and State of New York, has invented a new and useful improvement in the mode of applying the compound lever power, called "the compound Balance Lever Proprietary" and may be used either jointly or separately. The following is a description of the construction and operation of said machine as invented by me. A bottomed frame of a frame of suitable size with, one, two, three, four, five, six, seven, eight or more posts or standards of suitable size & length, formed in an upright, horizontal or angling position & framed together in such a manner as will be most conducive to the strength that it will stand, using square posts or standards to be placed at each distance from each other as is most convenient to perform the work, it is intended to do, with a sufficient number of frames at each end of said posts or standards to keep the frames together in its proper place, first of said posts may be extended beyond the others for the purpose of attaching a pulley to said posts or otherwise to work the lever or levers, together with one two or more platforms, following bears or lifting, with two or four posts bearing or moving up and down or otherwise between them, or around said posts, standards or frames as may seem best at one or both ends, or sides of said frame to place or remove their metal shaft or axle which may be square round, or at angles, or otherwise and generally at each end, and in the center or center of it is found, necessary, a round shaft or axle projects as many arms, wings or flanges, as may be necessary, from one end, these arms are made of parts of suitable length, breadth & thickness, standing out from the shaft or

note from one side more than a mere side, or part, parallel or from other side, or both at right or oblique angles from the timber shaft or axle. the number may be varied to suit circumstances, from two upwards to any number required, or may be constructed, with a cylinder and shaft or axle, with holes or mortises, similar to the head of a capstan of a ship or vessel, to which bars, or bars, may be applied for guidance, fairly or horizontally - which together with said shaft or axle, arms, wings, or flanges or cylinders as described above constituting the fulcrum or connection of power (commonly called the main fulcrum) in consequence of its moving or vibrating on its axis, central or journal. The ends of said arms, wings or flanges are so constructed as to receive the ends of what is termed the box bar which are attached to said fulcrum by means of bolts, rivets or otherwise most convenient. The other ends of said bars are attached to platters following beams, left or cross beams at each end by impost blocks, or otherwise and so riveted similar to the connection of said bar with the fulcrum which forms the connection between the fulcrum and the platters, following beams, left or cross beams: said box bars are formed or made, each of one bar or piece of iron or other metal either straight or curved with holes in each end of proportion to receive the bolts or rivets, when from the connection between the fulcrum and the platters, following beams, left or cross beams, to the box bars which may be attached to said platters, following beams, left or cross beams, as is most convenient, or if in case the shafts to be used on said shaft or axle instead of the arms, wings or flanges in that case it will be necessary to substitute chains of iron or other metal for the box bars to be connected similarly to said platters, following beams, left or cross beams and be attached to and around, the timber shaft or axle, in order to reduce the space between the platters, following beams, left or cross beams. In case the cylinder or said bars of wood or iron may be used, same to hang over in a capstan and acted as a lever, but, in case the arms, wings or flanges are used on said shaft or axle, they will be allowed to rise or move freely by means of iron rings, bars and bolts.

or otherwise to said bars, by which means they are made to act upon the fulcrum (thrusters are called the acting bars) in consequence of its performing a casting on the fulcrum the violent action in consequence of lifting or both jointly together as circumstances may require by means of the connection between the fulcrum by the lever being on chains being connected with the plattin follows, levers lifting or cross beams, or the end of the slender shaft or rod which may be of sufficient length to pass through the part with a cog, indus as described above, on one end of said shaft or rod instead of the centre, and be worked by bars above, this bar above, when placed perpendicular and attached to the fulcrum will bring the arms wings or flanges to a horizontal position (a little angling) thereby drawing the bars down to a horizontal position by hand with a wheel and windlass, or by the action of horse power or steam power or otherwise will cause the arms wings or flanges to swing to a perpendicular position acting on its centre consequently passing and lifting at the same time and reducing the span between the plattin, &c. The length of the fulcrum at each motion of the bars from a perpendicular to a horizontal position & vice versa said power and lifting may be constituted of wood and iron or of brass or other metal and are intended for all the purposes requiring a power lifting or both jointly in every variety of shapes and forms on the above principle but especially to lift the passing and compassing cotton, flax, wool, hay, & other tobacco, flowers, &c &c, casting &c and pieces of every description. Whether passing and cutting and all kinds of metals pointing in every variety, paper in every state, lifting and finishing dry roots of every description lifting & raising water by pumps or otherwise lifting or raising vessels of every description and above the water and propelling them through it with velocity — What I claim as my invention is which it does to secure by rollers, & other contrivances described mode of applying the lever power and connecting the fulcrum with arms wings or flanges projecting from bars there on some sides to parts of
